UNITED STATES PATENT OFFICE.

WALTER EVERETT MOLINS, OF LONDON, ENGLAND.

APPARATUS FOR PACKING CIGARETTES AND THE LIKE.

1,188,368.

Specification of Letters Patent. Patented June 20, 1916.

Application filed March 3, 1916. Serial No. 81,929.

To all whom it may concern:

Be it known that I, WALTER EVERETT MOLINS, a citizen of the United States of America, residing in London, England, have 5 invented certain new and useful Improvements in Apparatus for Packing Cigarettes and the like, of which the following is a specification.

The present invention relates to a packing machine in which the articles to be packed, such as cigarettes or the like, are continuously fed to moving carriers, arranged on an endless conveyer at suitable distances from each other and running between side or guide cheeks.

The feed of the article to be packed is effected by means of endless bands arranged at right angles to the above-mentioned endless conveyer, from which bands the articles 20 are pushed or swept down on to the longitudinal conveyer by means of a further band provided with sweepers.

The counting or distribution of the articles into groups of certain number is 25 effected by vertically adjustable retaining plates provided above the feed band, which periodically descend on to the feed band and arrest the movement of the articles being fed forward and collect them in groups.

30 The invention will be fully described with reference to the accompanying drawings, in which one form of apparatus constructed according to the invention is illustrated diagrammatically.

35 Figure 1 is a side elevation of the machine. Fig. 2 is a plan of same, and Fig. 3 is a sectional side elevation. Fig. 4 is a sectional side elevation similar to Fig. 3 showing a modified form of stop plate.

40 An endless conveyer band or chain 2 runs under the table 1 and is provided at intervals with carriers or pushers 3, which project through and move along a slot in the table 1. Above the table 1 and at right angles to this conveyer band 2 are arranged feed bands 4, above which again is arranged a short endless band 5 in line with and above the conveyer 2 and provided with sweepers 6. At the side of this last 45 band 5 is provided a plate 7, capable of vertical movement and which can be depressed on the bands 4. There are further, preferably arranged on the table 1, side cheeks 8, which guide the articles forward 50 and prevent any lateral movement of them as they are fed along the table.

It will be obvious by mere duplication of feed bands 4, so as to provide a series of parallel bands, the articles may be supplied to the main carrier 2 in layers.

The operation of the machine is as follows, as applied by way of example to the packing of cigarettes: The cigarettes are arranged at short distances from each other on the feed bands 4 and are continuously 65 fed to the table by this constantly traveling band. The plate 7 is, however, periodically lowered in front of the cigarettes on the band 4 and so causes the cigarettes to be collected together in groups. As soon as 70 the desired number, for example 5, is obtained, the plate 7 is lifted and this group of five cigarettes is now at once conveyed under the sweeper band 5 and swept by one of the sweepers 6 from the band 4 on to the 75 table 1, where the next carrier 3 conveys the group along the table 1. The cigarettes are now fed by the continuously moving band 2 or the carrier 3 to the package awaiting it, which in turn is conveyed in the 80 known manner to the other parts of the packing machine.

The plate 7 may be at an angle to the feed band 4, so that when feeding oval cigarettes these can be placed on edge or inclined as 85 required by the oscillating plate.

Having thus described my invention and the best means I know of carrying the same into practical effect, I claim:

1. Packing apparatus, especially applicable for packing cigarettes and similar articles having, in combination, a continuously moving band provided with pushers at fixed intervals, a second continuously moving feed band arranged above and at 90 right angles thereto, and a third continuously moving band arranged above said feed band and provided with sweepers to deliver cigarettes from said feed band to said first named band, substantially as herein described.

2. Packing apparatus, especially applicable for packing cigarettes and similar articles having, in combination, a continuously moving band provided with pushers at 105 fixed intervals, a second continuously moving feed band arranged above and at right angles thereto, a vertically moving plate arranged above said feed band and adapted to engage and group the cigarettes at pre-determined intervals, and a third continuously moving band arranged above said 110

feed band and provided with sweepers to deliver cigarettes from said feed band to said first named band, substantially as herein described.

- 5 3. Packing apparatus, especially applicable for packing cigarettes and similar articles having, in combination, a continuously moving band provided with pushers at fixed intervals, a second continuously moving feed 10 band arranged above and at right angles thereto, a vertically moving plate arranged above the said feed band and at an angle thereto for engaging and inclining or raising on edge oval cigarettes and grouping them at predetermined intervals.
- 15 4. Packing apparatus, especially applicable for packing cigarettes and similar articles having, in combination, a continuously moving band, a second continuously moving feed band arranged above and at right angles thereto, and a third continuously moving band arranged above said feed band and traveling in a direction parallel to the first mentioned band, and provided with means 20 for sweeping cigarettes from said feed band to said first mentioned band.
- 25 5. Packing apparatus, especially applicable for packing cigarettes and similar arti-

cles having, in combination, a continuously moving band, a second continuously moving feed band arranged above and at right angles thereto, and a third continuously moving band arranged above said feed band, and provided with sweepers to deliver cigarettes from said feed band to said first named band, and traveling in a direction parallel to the first-mentioned band.

6. Packing apparatus, especially applicable for packing cigarettes and similar articles having, in combination, a continuously moving band provided with pushers at fixed intervals, a second continuously moving band arranged above and at right angles thereto, and a third continuously moving band arranged above said feed band and provided with sweepers to deliver cigarettes from said feed band to said first named band and traveling in a direction parallel to the first band.

In testimony whereof I have signed my name to this specification in the presence of two subscribing witnesses.

WALTER EVERETT MOLINS.
